By James L. Norris.

UNITED STATES PATENT OFFICE.

CHARLES A. RANDALL, OF NEW YORK, N. Y.

TELEPHONE SYSTEM AND APPARATUS.

SPECIFICATION forming part of Letters Patent No. 271,513, dated January 30, 1883.

Application filed September 11, 1882. (No model.)

To all whom it may concern:

Be it known that I, CHARLES A. RANDALL, a citizen of the United States, residing at New York city, in the county and State of New York, have invented new and useful Improvements in Telephone System and Apparatus, of which the following is a specification.

This invention relates to that class of telephone-exchange systems and apparatus in which the subscribers' lines radiate from a switch-board at a central office provided with apparatus for receiving and transmitting calls.

The objects of the invention are to facilitate the receipt and transmittal of calls at and from the central office; to enable the switch-board operator to know at all times what subscribers' lines are in use without "cutting in," and to effect automatically the cutting in and out of circuit the several apparatus at the subscribers' offices, as required.

The invention consists in certain novel constructions and combinations of devices for accomplishing these objects, as will be hereinafter described, and pointed out in the claims.

25 In the drawings, Figure 1 is a view in elevation of the apparatus at the central office and a single connected subscriber's station. Fig. 2 is a diametric section of the switch-board, in the line $x-x$ of Fig. 1.

30 The letter A indicates the base or supporting board of the switch-board. It is made of wood or other non-conducting material, and is provided on its front with a central metallic plate, D², which by a wire, d, is connected with a receiving-telephone, D³, which is connected with a transmitter, D⁴, which is in turn connected with the ground through a battery, B².

35 In a circle around the plate D² are arranged a series of individually insulated metallic blocks, indicated by the numerals 1 2 3 4, &c. These blocks are connected with the central-office terminals of the subscribers' lines, respectively, and each is provided with an attached connector, C, and a plug-socket, s, each connector being provided with a plug, c, which fits all the sockets. Each connector C is made of a metallic spring strip or wire doubled in the form of a letter U and has the end of one leg in swiveling connection with its block, while the other leg is slightly shorter and pro-

vided with a plug of such size that it will be held by friction in any of the switch-board plug-sockets. The connector may be easily flexed, so that its plug may form the connections hereinafter described, and will resume its normal shape when the plug is released. The precise shape of the connector is not material. It may have several bends or one or more coils formed in it, if desired, the main object being to have it of such resilience that it will stand out from the board and resume its position when left free after use, so that it will not become entangled with other connectors.

45 Outside the circle of numbered blocks is arranged a metal ring, B, which is provided with a socket, s', behind each block, and said ring is connected by a wire, b, with a call-operator's receiving-telephone, B', which is connected with a transmitter, B², in the usual manner, and the transmitter is connected to ground.

50 Surrounding the ring B and insulated therefrom is another metallic ring, D, which is connected with the central plate, D², by a wire, d², (indicated by a dotted line.)

The several terminal blocks 1 2 3 4, &c., are respectively connected with the coils of magnets N' N² N³ N⁴, and so on, and these coils are connected with the respective subscribers' lines, the office of the magnets being to indicate to the switch-board operator when the lines to which they are connected are in use, and thereby obviate the necessity of his connecting his telephone with any line in order 55 to ascertain if it be in use or if conversation has been discontinued over two lines which have been connected. If any line is in use, the magnet connected in that line will attract its armature, owing to its being then connected in 60 circuit with the subscriber's battery, as will presently appear.

55 The letter w indicates a wire connecting the terminal block 1 of the switch-board with one terminal of the coils of indicating-magnet N', the other terminal of said coils being connected with the subscriber's line W, which leads to "Subscriber's Station No. 1," which is so marked on the drawings. At the subscriber's station the line W divides at the point marked y, one 65 branch, H, leading to the receiver R, and connected therewith in a manner presently to be

described, while the other branch, H' , leads to the transmitter T and connects with one terminal of the secondary circuit of its induction-coil, the other terminal connecting through a switch, h , with one pole of the station-battery G , from the other pole of which a wire, g , leads to the receiver. From the wire g leads a branch wire, h' , terminating in a contact-plate, h^2 , with which the switch h is adapted to be brought in contact for the purpose of cutting out the battery.

The receiver R has attached to its case a laterally-projecting tube, R' , of insulating material, within which are two pairs of metallic and preferably elastic fingers, $r^1 r'$ and $r^2 r^3$, the pair of fingers $r^1 r'$ projecting toward the middle of the tube from one end, while the pair $r^2 r^3$ project toward the middle from the opposite end. In the space between the ends of the two pairs of fingers is a loose metallic ball, M , and when the tube R' extends upward with respect to the case of the receiver, as shown in Fig. 1, the metallic ball M will rest upon and electrically connect the fingers r^2 and r^3 ; but if the tube R' is reversed the ball will rest upon and connect the fingers $r^1 r'$. The branch H of the line-wire connects with the finger r^2 , and from the finger r^3 a wire, I , connects with one terminal of the coils of the bell-magnet K , from the other terminal of which a wire, I' , leads to ground. When the receiver R and tube R' are in the position shown in the drawings, which is their normal position when hung up and not in use, it will be observed that the line-wire W is connected to ground through branch H , finger r^2 , ball M , finger r^3 , wire I , bell-magnet coils, and wire I' , so that the subscriber may receive a call through his bell when a current is sent over his line-wire. The wire g , which connects with the branch H' through battery G and transmitter T , is connected with the finger r , while from the finger r' a wire, g' , leads to one terminal of the coil of the receiver-magnet, (not shown,) and from the other terminal of said coil a wire, g^2 , connects with wire I' , and through it to ground. It will now be seen that if the position of the receiver be reversed from that shown in the drawings, as before described, the ball M will connect the fingers r and r' , and the line W will be connected to ground through branch H' , the transmitter T , battery G , wire g , finger r , ball M , finger r' , wire g' , receiver-coil, wire g^2 , and a part of wire I' , the station apparatus being thus in condition for holding conversation with another station or the central office. At the same time the bell-magnet will be cut out of circuit, as the fingers r^2 and r^3 are not connected. At this time, also, the current from battery G traverses the line-wire and charges the magnet N at the central office, which, by its action upon its armature, gives notice to the switch-board operator that the line is in use.

At the central office the plugs c of the connectors C are kept normally in the sockets s' ,

behind their respective metal blocks 1 2 3 4, &c. When a subscriber—say, for instance, subscriber No. 1—wishes to communicate with another subscriber—say subscriber No. 4—he first puts his apparatus in condition for use, as just described, the circuit being completed from his battery over his line-wire W , coils of magnet N' , terminal block 1 at switch-board, its connecting end C , metallic ring B , and wire b , and through the call-operator's instruments to ground. He then informs the call-operator with whom he wishes to communicate, and the call-operator thereupon directs the switch-board operator to connect subscribers' lines 1 and 4. The switch-board operator then first calls up subscriber No. 4. This he does by removing the plug of the connector C of terminal block 4 from its socket in ring B and placing said plug in contact with the central plate, D^2 , or ring D , thus connecting the subscriber's line No. 4 with the ground through the connector C , plate D^2 or ring D , wire d , the switch-operator's instruments, and battery B^2 . The current of battery B^2 flows over the line No. 4 and rings the bell at the subscriber's station. When subscriber No. 4 receives the call he first changes his switch to contact with plate h^2 , places his receiver in position for use, and replies through his transmitter that he is ready. The switch-board operator then connects the two lines by inserting the plug of connector C of block 4 in the socket of the terminal block 1, and disconnecting the plug of the connector of block 1 from ring B , and allowing said connector to hang free; or the connection between the two blocks could be made through the connector of block 1 and the connector of block 4 be left to hang free. The subscribers' lines being thus connected through their switch-board terminal blocks and the connectors, a current will traverse the connected lines from the battery of subscriber No. 1, as has been already fully explained, and the indicating-magnets N' and N^4 at the central office will show the switch-board operator that these two lines are in use, and no other connection must be made therewith until the indicating-magnets show that no current is traversing the lines and the conversation has been finished. The two lines are then to be reconnected with the call-operator's instruments through their terminal blocks 1 and 4, connectors C , ring B , and wire b . When a subscriber receives a call his first step is to cut out his battery by changing the switch h to plate h^2 , in order that it may not be in opposition to that of the switch-board operator when the subscriber puts his receiver in position for use, or to that of the calling subscriber when two lines are connected. It is obvious, however, that the called subscriber might, instead of cutting out, reverse his battery by means of suitable switch-connections, so that it would work in correspondence with another battery in circuit.

From the foregoing description it will be seen that the switch-board operator may at

any time call any subscriber with whom the central office desires to converse.

The magnets N^1 , N^2 , N^3 , N^4 , &c., may serve as annunciators by fitting them with suitable drops; or vibrating armatures or pointers may be used.

I do not confine myself to the precise construction of apparatus shown, but reserve to myself the right to make such changes therein as legitimately come within the scope and spirit of my invention.

I am aware that the terminals of subscribers' lines at a central office have been provided with attached flexible connections carrying switch-plugs, and that switch-plates have been provided to receive said plugs for making connections, and I do not claim such an arrangement.

What I claim is—

1. A telephonic central-office switch - board provided with metallic line terminal blocks or plates, each of which is provided with a permanently electrically-connected connecting device provided with a switch-plug, and each of said blocks or plates being also provided with a plug-socket to receive the plugs of said connecting devices, respectively, substantially as described.

2. The switch-board having a metallic plate adapted for connection with battery or ground, the circular series of metallic line terminal blocks, and the metallic ring B, adapted for connection with a call - operator's instruments

and for plug-connection with the line terminal blocks, respectively, substantially as described. 35

3. The combination, with the switch-board, of the circuit including the call-operator's instruments and ring B, the circuit including the switch-board operator's instruments and plate D², and the line-circuits, including the metallic 40 terminal blocks and connectors C, substantially as described.

4. The combination, with the subscribers' lines and batteries and the switch - board terminals and intermediate connections, of the 45 indicating - magnets and devices at the subscriber's office for automatically connecting the station-batteries in circuit with said indicating-magnets when the station apparatus is in use, and switches at the stations for cutting 50 the batteries out of the line, as required, substantially as described.

5. The combination, with the terminal blocks having plug-sockets, of the outwardly-standing loop-shaped flexible wire-connections 55 C, each having one leg swiveled in a terminal block and the other leg free and provided with a plug to fit the said plug - sockets, substantially as described.

In testimony whereof I have hereunto set my 60 hand in the presence of two subscribing witnesses.

CHARLES ADAMS RANDALL.
